(57) **CLAIM**

The ornamental design for a trekking pole handle as shown and described.

DESCRIPTION

FIG. 1 is a perspective view of a trekking pole handle according to the invention.

FIG. 2 is a front view of the trekking pole handle of FIG. 1.
FIG. 3 is a rear view of the trekking pole handle of FIG. 1.
FIG. 4 is a right side view of the trekking pole handle of FIG. 1.

FIG. 5 is a left side view of the trekking pole handle of FIG. 1.

FIG. 6 is a top view of the trekking pole handle of FIG. 1.
FIG. 7 is a bottom view of the trekking pole handle of FIG. 1.

FIG. 8 is a perspective view of the trekking pole handle of FIGS. 1 through 7 with a cap removed.

FIG. 9 is a front view of the trekking pole handle of FIG. 8.
FIG. 10 is a rear view of the trekking pole handle of FIG. 8.
FIG. 11 is a right side view of the trekking pole handle of FIG. 8.

FIG. 12 is a left side view of the trekking pole handle of FIG. 8.

FIG. 13 is a top view of the trekking pole handle of FIG. 8.
FIG. 14 is a bottom view of the trekking pole handle of FIG. 8.

FIG. 15 is a perspective view of the cap portion of the trekking pole handle of FIGS. 1 through 7.

FIG. 16 is a front view of the trekking pole handle of FIG. 15.

FIG. 17 is a rear view of the trekking pole handle of FIG. 15.
FIG. 18 is a right side view of the trekking pole handle of FIG. 15.

FIG. 19 is a left side view of the trekking pole handle of FIG. 15.

FIG. 20 is a top view of the trekking pole handle of FIG. 15; and,

FIG. 21 is a bottom view of the trekking pole handle of FIG. 15.

The broken line showing the trekking pole in FIGS. 1 through 14 are provided for purposes of environment and form no part of the claimed design.

1 Claim, 12 Drawing Sheets
